(57) **CLAIM**

The ornamental design for a billiard-cue tip, as shown and described.

DESCRIPTION

FIG. 1 is a bottom back perspective view of a billiard-cue tip;
FIG. 2 is a top front perspective view thereof;
FIG. 3 is a top plan view thereof;
FIG. 4 is a front view thereof; and,
FIG. 5 is a bottom plan view thereof.

The broken lines showing environmental structure is for illustrative purposes only and form no part of the claimed design.
